(57) **CLAIM**

I claim the ornamental design for dresser and mirror, as shown and described.

DESCRIPTION

FIG. 1 is a perspective view of a dresser and mirror according to an embodiment of the invention.

FIG. 2 is a front elevational view of a dresser and mirror according to an embodiment of the invention.

FIG. 3 is a front elevational view of a dresser and mirror according to an embodiment of the invention; and,

FIG. 4 is a side elevational view of a dresser and mirror according to an embodiment of the invention.

The features shown in broken lines and the black dots representing holes for drawer handle attachment form no part of the claimed design.
